PAPER GUIDING IN CIGARETTE ROD
MACHINES

Richard Erich Rösler, Dresden, Germany, assignor to Universelle Cigarettenmaschinen-Fabrik J. C. Müller & Co., Dresden, Germany

Application November 30, 1931, Serial No. 578,098, and in Germany March 27, 1931

10 Claims. (Cl. 131—43)

This invention relates to a cigarette rod machine with an adjustable guide for the paper strip.

In cigarette rod machines, wherein the cigarette paper has a relatively long guide, for example in such machines wherein the tobacco is brought directly upon the paper, there is the disadvantage that the paper is not always in the correct position at the place where the adhesive is applied, so that the strip of adhesive also is not always in the correct place. It is already known to pass the paper strip, for the purpose of aligning it, through a guide before its introduction into the tipping and printing apparatus, and to make the said guide laterally adjustable. This device is not immediately applicable for guiding the paper on its introduction to the adhesive-applying place, because at that place the paper is already curved, and a lateral displacement of the paper would cause the strip to tear.

In order to secure accurate positioning of the strip of adhesive on the paper, the guide for the paper, which part is provided in front of the place where the adhesive is applied, is so arranged according to the invention that it is rotatable about, or approximately about, the axis of the cigarette rod. The lateral edges of the paper strip may then be aligned relatively to the adhesive-applying apparatus by rotating the guide.

One constructional example is shown in the accompanying drawings, wherein

Figure 1 is a front view, and

Figure 2 is a side view.

Figure 3 is a diagrammatical view of a part of a cigarette rod machine showing the arrangement of the guide according to the invention in combination with other parts.

The paper strip *a* indicated in Fig. 3 by a dot and dash line is drawn off from a roller *m* journaled in the machine frame *M*. The paper strip runs over a set of rollers *m*¹ through the printing apparatus indicated by the reference letter *n* and from here over another set of rollers *n*¹ into the U-shaped chute *o* arranged beneath the tobacco carding device, the under part of which is designated with the reference letter *p*. The tobacco falls from the carding apparatus onto the paper strip within the chute *o* in the form of a thin film and is conveyed with the paper strip.

An endless band *t* also indicated by a dot and dash line is guided over a set of rollers *u* into a chute *v* forming a continuation of the chute *o*. This band receives the paper strip with the tobacco and forms it into a rod. For this purpose an apparatus *w* is arranged which folds the end

of the paper strip by means of the band together, and the so folded paper strip containing the tobacco is brought to the adhesive applying apparatus *q* which applies the adhesive to the edge of the paper strip and then presses the paper edges together so that a cigarette rod *s* forms. This rod is afterwards cut into respective lengths by means not illustrated in the drawings.

The parts and the arrangement of the machine described until now are or may be of known construction. According to the invention improved adjustable guiding means are provided for the paper strip before it is introduced into the adhesive applying apparatus *q*. This improved guiding means designated in Fig. 3 as a whole with the reference letter *r* is illustrated in details in Figs. 1 and 2 of the drawings.

The purpose of the improved guide is to provide an accurate adjustment of the paper strip before it enters the adhesive applying apparatus and is provided with adhesive. The guiding means comprises a guide or adjustable member *b* constructed U-shaped in cross-section. The bottom is curved and corresponds to the shape which the paper strip assumes at this place. The paper strip passes through the said guide *b*, being held therein by two lateral plates *c* and *d*, which are fixed to the two lateral limbs of the U-shaped guide or member *b* by means of bolts *e*. The bolts *e* are situated in slots in the limbs of the guide *b*, so that the plates *c* and *d* can be adjusted higher or lower, this adjustment being effected in order to adapt the apparatus to different widths of paper. The plates are so adjusted that they guide the paper accurately, that is to say, they prevent the paper from rising to the one side or the other. The guide *b* is provided with an extension *f*, the lower face of which has the form of a worm wheel, having its axis coinciding, or approximately coinciding, with the axis of the cigarette rod which is to be formed. The said worm wheel meshes with a worm *g* journaled in a bearing bracket *h* on the machine frame, and adapted to be rotated by means of hand wheel *i*. The guide *b* or its extension *f* is likewise guided in the bracket *h*, lateral pins *k* on the extension *f* engaging arcuate slots *m* in the bracket *h*.

The paper strip on emerging from the guide *b* reaches the adhesive-applying place, where the adhesive is applied.

The mode of operation of the device is consequently as follows:

If the attendant of the machine observes that the adhesive is being incorrectly applied, that is

to say, that the adhesive applying roller meets the paper strip either too far from the edge, or that the adhesive is not applied in the correct width upon the paper strip, he has merely to rotate the knob *i* in one or the other direction. The whole guide *b* then rotates in one or the other direction about, or approximately about, the axis of the cigarette rod, and consequently the paper strip is moved in one or the other direction relatively to the adhesive roller, and is thereby brought into correct engagement with the adhesive roller, without being moved out of the direction of the rod itself.

Of course, other constructional means may also be selected for guiding and adjusting the band, thus, for example, a guide in a cam, a helical gear drive or the like may be used instead of the worm wheel drive.

I claim:—

1. A cigarette rod machine comprising in combination with the means for guiding the paper strip and the means for applying the adhesive to the paper strip, an adjustable guide for the strip provided in front of the adhesive applying means and means for rotating said guide about an axis coinciding with the axis of the cigarette rod for the purpose to adjust the guide.

2. A cigarette rod machine comprising in combination with the means for guiding the paper strip and the means for applying the adhesive to the paper strip, an adjustable guide for the strip provided in front of the adhesive applying means, a worm wheel provided on the guide, the axis of which worm wheel coincides with the axis of the rod and a manually operated worm meshing with said worm wheel for the purpose of rotating said wheel and guide thereby adjusting the guide.

3. A device for adjusting the guide of a paper strip particularly for cigarette rod machines, comprising means for moving the guide around an axis approximately coinciding with the axis of the cigarette rod to shift the paper strip to travel the desired path and position.

4. A device for adjusting the guide of a paper strip particularly for cigarette rod machines, comprising means for imparting a rocking movement at right angles to the direction of travel of the paper strip around an axis approximately coinciding with the axis of the cigarette rod to thereby shift the strip to travel the desired path and position.

5. A device for adjusting the path of a paper strip particularly for cigarette rod machines, comprising a guide of approximately U shape through which the paper strip passes; a plate secured to each straight side of the U-shaped guide for the paper strip; and means for moving the guide laterally relative to the direction of movement of the paper strip to thereby shift the strip to travel the desired path and position.

6. A device for adjusting the path of a paper strip particularly for cigarette rod machines, comprising a guide of approximately U shape through which the paper strip passes; a plate secured to each straight side of the U-shaped guide for the paper strip, said plates being movably mounted to render them adjustable to accommodate the guide to different widths of paper; and means for moving the guide laterally relative to the direction of movement of the paper strip to thereby shift the strip to travel the desired path and position.

7. A device for adjusting the path of a paper strip particularly for cigarette rod machines, comprising a guide of approximately U shape through which the paper strip passes; a plate secured to each straight side of the U-shaped guide for the paper strip; and means including a pair of intermeshing worm gears for moving the guide laterally relative to the direction of movement of the paper strip to thereby shift the strip to travel the desired path and position.

8. A device according to claim 7 and a bracket in which the guide and the worm gears are mounted.

9. A device according to claim 7 in which a bracket is included and the guide is provided with an extension, projecting into the bracket and having one of the worm gears thereon, the other worm gear being rotatably mounted in the bracket.

10. A device according to claim 7 in which a bracket is included and the guide is provided with an extension projecting into the bracket and having one of the worm gears thereon, the other worm gear being rotatably mounted in the bracket; and including also lateral pins on the extension engaging the bracket for guiding the guide in the bracket.
